AIR DISCHARGE MEMBER FOR HEATING SYSTEMS

Louis C. Cotts, Michigan City, Ind.

Application June 21, 1954, Serial No. 31,090

Term of patent 14 years

(Cl. D81—21)

FIG. 1.

FIG. 2.

To all whom it may concern:

Be it known that I, Louis C. Cotts, a citizen of the United States, residing at Michigan City, in the county of La Porte, State of Indiana, have invented a new, original, and ornamental Design for an Air Discharge Member for Heating Systems, of which the following is a specification, reference being had to the accompanying drawings, forming part thereof.

Fig. 1 is a front elevation of an air discharge member for heating systems, incorporating my new design; and Fig. 2 is a front perspective view thereof.

I claim:

The ornamental design for an air discharge member for heating systems, as shown.
